UNITED STATES PATENT OFFICE.

HARRIETTE E. HODGSON, OF NEW YORK, N. Y.

FIRE RESCUE BAG.

Application filed June 16, 1921. Serial No. 477,873.

To all whom it may concern:

Be it known that I, HARRIETTE E. HODGSON, a citizen of the United States, and a resident of the borough of Manhattan, in the city, county, and State of New York, have invented a new and useful Fire Rescue Bag, of which the following is a specification.

The object of this invention is to provide a simple and efficient device in the nature of a bag by means of which adults or children can be lowered safely from a burning building. Another smaller form of the device is adapted to be carried on the fireman's back for rescuing infants. The bag has flexible sides and bottom of suitable strong material, fabricated so as to produce a doubled or multiple thickness at the bottom with the seams above the bottom where they will not pull out. Externally the walls of the bag are restrained and reinforced by the rope netting, to which is connected either the lowering means or the means for strapping upon the back. Other features of the forms 25 of the invention will become apparent as the specification proceeds.

In the accompanying drawings forming a part hereof:

Fig. 1 is a face view of the form of the bag which is lowered, the lowering cable being shown broken away at intervals to indicate an indefinite length;

Fig. 2 is a view looking at right angles to Fig. 1;

Fig. 3 is a view on a small scale showing the device in use for lowering a person from a burning building;

Fig. 4 is a section through the lower portion of the bag;

Fig. 5 is a face view of the smaller form of the bag, which is adapted to be carried upon the back;

Fig. 6 is a view looking at right angles to Fig. 5; and

Fig. 7 is a view showing this form of the device being carried upon the back of a fireman.

Reference will first be had to Figs. 1 to 4.

The bag proper, designated 1, is of a flat oblong form, adapted to be lowered down the face of a building without catching on projections, and is preferably made of some strong textile fabric treated with asbestos. As illustrated in Fig. 4, the bottom and the lower portions of the sides are made in a double thickness by carrying each side down

around the bottom and for a suitable distance up the other side, so that the two parts overlap, the ends being secured to the side walls by stitching 2 at a substantial height above the bottom where the stitching is not subject to special strain. The top of the bag is open, though fastening means might be provided if desired.

The bag is enclosed by a network 3 composed of a multiplicity of vertical cords 4 and horizontal cords 5 connected in a rectangular mesh. The vertical cords are preferably knotted to the horizontal cords, as indicated at 6, and knots 7 in the horizontal cords at opposite sides of each knot 6 keep the members from displacement on each other. Eyes 8 are sewed to the upper portion of the bag, and through these pass the vertical cords, which are thus held against displacement on the bag. Other eyes 9 on the edges or narrow sides of the bag have the horizontal cords passed through them, and still other eyes 10 at the bottom confine the horizontal cords at this region.

The vertical cords are extended above the top of the bag and are brought together in two groups 11, 11^a at opposite sides of the center of the wide sides of the bag, each group comprising cords extending from both lips of the bag, as seen in Fig. 2. The cords of the two groups are tied together in separate knots, marked, respectively, 12 and 12^a. From the knot 12 one-half of the strands 13 is extended a short distance upward to a knot 14, and the other half 15 is extended across to a knot 14^a. In like manner one-half 13^a of the strands from the knot 12^a is extended upward and incorporated in the knot 14^a, while the other half 15^a is carried across and incorporated in the knot 14. From the knot 14, one-half 16 of the strands included therein is extended outward to a knot 17, and the other half 18 is extended across to a corresponding knot 17^a at the opposite side. In like manner one-half 16^a of the strands from the knot 14^a is extended outward to the knot 17^a and the other half 18^a is extended across to the knot 17. The multiple strands 18 and 18^a, where they cross, are knotted at 19. In this way a very strong arrangement is secured and one which tends to keep the net spread. The multiple strands 16 and 18^a at one side, and 16^a and 18 at the opposite side, constitute a first pair of flexible

grasping or lowering handles.

The lower portion 20 of a multiple-stranded lowering cable 21 is looped through the middle of the cord assembly constituted by the upward extension of the vertical members of the bag network. This cable is of any suitable length, depending upon the height of the building in which it is to be used, and is provided at convenient intervals with pairs of loop members 22 for convenience in lowering.

One of these bags is of a size to contain and completely enclose a person, or even two persons, and several children, and together with its network is of such strength as to hold them beyond any possibility of disaster. The manner of lowering the bag thus loaded from the window of a burning building will be obvious.

The smaller form 1^a of the bag shown in Figs. 5, 6 and 7 is of like construction and is provided with a generally similar network 3^a. This form illustrates the fact that the vertical and horizontal cords of the network at the intersections may be passed through common eyes 25 on the outside of the bag, knots 26 being tied in both cords at opposite sides of the eye to prevent displacement. Other eyes 27 and 28 may be used toward the narrow sides and at the bottom. The two cords of the network at each side are extended upward through other eyes 29 on the bag, near the top, and are united or made continuous to form carrying loops 30. Two cords 31 are disposed on the front side of the bag, extending diagonally upward and inward from the network at the opposite ends or narrow sides of the bag to the loops 30. These cords 31 constitute shoulder loops through which the fireman passes his arms, as shown in Fig. 7.

Two rope or strap members 32 are also secured to the network at about the middle height toward the opposite ends or narrow edges of the bag, these members being adapted to be tied around the body of the fireman

as seen in the said view. In the lips of the bag cords 33 are provided for tying the top of the bag so as to keep the child from climbing or exposing its head. If desired, the fireman can put the loops 30 over his head.

Additional ropes 5^a may be attached to the form of bag shown in Fig. 1, for the purpose of holding the persons in more securely and making the bag easier to handle. These cords, and more particularly the upper ones, may be used for tying the person or persons in the bag, and if allowed to hang free they may also be used as handles for drawing in the bag when it comes opposite a lower window.

I claim:

1. A fire-rescue device comprising a flat bag of flexible material, an enclosing network of vertical and transverse strands, the vertical strands being brought together in two groups and knotted together above the top of the bag, and a lowering cable which is looped through this knotted structure.

2. A fire-rescue device comprising a bag of flexible material, and a reinforcing net completely enclosing the sides and bottom.

3. A fire-rescue device comprising a bag of flexible material, a reinforcing net completely enclosing the sides and bottom of said bag, and connections between said net and said bag whereby displacement of the elements of said net relatively to said bag is prevented.

4. A fire-rescue device comprising a bag of flexible material having each of two of its opposite sides extended downwardly around the bottom of the bag and upwardly along the other of said two sides and secured to said other side at a point above the bottom, thereby providing a double bottom with seams at the sides and above the bottom, and a reinforcing net enclosing said bag.

HARRIETTE E. HODGSON.
